LIQUID DIVERTING APPARATUS

Winifred E. Parks, Los Angeles, and Harold W.
West, Lynwood, Calif.

Application September 21, 1951, Serial No. 247,662

1 Claim. (Cl. 251—125)

1

The present invention relates generally to liquid diverting apparatus and more particularly to novel apparatus for selectively diverting the flow of water in a pipe from its normal course into a second pipe.

In many parts of the United States, there now exists a continuous, or at least a seasonal shortage of water. This water shortage appears to be steadily growing more pronounced, due to a gradual lowering of the water table through continued pumping at a rate in excess of the rate of replenishment. Even in those places where the water table is not dropping, it may have fallen so low that the cost of obtaining water is appreciable. In these water-short localities, it is essential that conservation of water be practiced wherever possible. In this respect, it will be apparent that much water is presently wasted by being allowed to enter the drain of sinks, shower baths, bowls and the like. Such water, although not suited for re-use in fulfilling human needs, is perfectly suited for re-use for other purposes where purity is not essential. Such purposes may include irrigation of lawns and shrubs, washing various items, such as windows and automobiles and many other similar purposes which will come to mind.

It is a major object of the present invention to provide a novel liquid diverting apparatus which will selectively divert the flow of water from its normal course, such as the drain of a sink, bowl or the like, into a storage container for subsequent re-utilization. It is another object of the present invention to provide a liquid diverting apparatus which is inexpensive to manufacture.

A further object of this invention is to provide a liquid diverting apparatus which may be utilized with conventional plumbing fixtures, without requiring other than incidental alteration thereof.

Another object of the present invention is to provide a liquid diverting apparatus which is sturdy of construction and foolproof in operation whereby it will require a minimum of repairs.

It is a further object of this invention to provide a liquid diverting apparatus which when installed properly will not be susceptible to leakage.

An additional object of the present invention is to provide a liquid diverting apparatus which may be installed and serviced by the use of standard tools.

Other objects and advantages of the present

2

invention will be apparent from the following detailed description of a preferred embodiment thereof, taken in conjunction with the accompanying drawing, wherein:

5 Figure 1 is a side elevation showing a sink incorporating liquid diverting apparatus built in accordance with the present invention.

Figure 2 is an enlarged fragmentary sectional view taken on a median plane of the apparatus 10 of Figure 1, and showing the parts thereof disposed in their normal or inoperative position.

Figure 3 is a view similar to Figure 2, but showing the parts of the apparatus in an operative or liquid diverting position.

15 Referring to the drawing, and more particularly to Figure 1 thereof, there is shown a conventional sink 10 having a drainpipe system, generally designated 12, wherein is interposed a liquid diverting apparatus, generally designated 14, constructed in accordance with the present invention. There is also shown a storage container 16 which communicates with the liquid diverting apparatus 14 by means of a pipe 18. Mounted upon the sink 10 is a control handle 20, 20 which handle is connected by a link 20a to the apparatus 14. It should be understood that normally water placed in the sink 10 will flow downwardly through the drainpipe system 12 into a waste or sewer system. At such time however that it becomes desirable to conserve such water, the control handle 20 may be moved so as to cause the liquid diverting apparatus 14 to divert the water through pipe 18 and into the storage container 16.

25 The details of construction of the liquid diverting apparatus 14 are clearly shown in Figures 2 and 3. This apparatus broadly comprises a sleeve, generally designated 22, formed with a first elbow 24 in its upper portion, and a second elbow 26 formed in its lower portion. The upper end of this sleeve 22 is adapted to be secured to a depending pipe 28 of the drainpipe system 12, while the lower end of the sleeve is adapted to be secured to a J-shaped portion 30 of this system. The first elbow 24 is shown connected to the pipe 18 leading to the storage container 16. The second elbow 26 supports a valve mechanism to be described in detail hereinafter. Both the upper and lower ends of the sleeve 22 and each of the elbows 24 and 26, respectively, are seen to be externally threaded.

30 Disposed concentrically within the sleeve 22 is a rubber cylinder, generally designated 32. This cylinder 32 is formed with an axial bore 34 and an intersecting radial bore 36. When disposed

within the sleeve 22, the bottom end of this cylinder is located below the first elbow 24 and above the second elbow 26 with its radial bore 36 aligned with the first elbow.

There is shown threaded upon the second elbow 26 a mounting element 38 for a generally cone-shaped valve 40. This element 38 includes a recess 42 which co-operates with the end of the second elbow 26 to rockably retain a ball or spherically-shaped support 44. The inner end of this support 44 mounts a rod 46 which extends into the sleeve 22 to about the mid-portion thereof. The distal end of this rod 46 is pivotally connected to an integral extension 48 of the lower end of the valve 40. A lever 50 is rigidly affixed to the remote side of the support 44. Hence, it should be understood that normally the valve 40 will assume the position shown in Figure 2 wherein it is seen to be disposed with its main portion below the bottom end of the rubber cylinder 32. If, however, the lever 50 is urged downwardly, the valve will be moved upwardly so as to seat against the bottom end of the cylinder, as shown in Figure 3.

In operation, referring again to Figure 2, water from the sink will normally flow downwardly through pipe 23 and axial bore 34, past the open valve 40, through the J-shaped portion 30 and into a waste or sewer system. When, however, it becomes desirable to conserve the water draining from the sink, the lever 50 may be urged downwardly whereby the valve 40 will be moved upwardly to seat against the bottom end of the rubber cylinder 32, as shown in Figure 3. In this manner, the downward flow of water through axial bore 34 will be blocked off and this water will be diverted through first elbow 24 and pipe 18 into the storage container 16. Movement of the lever 50 may conveniently be effected by the control handle 28, which handle is connected thereto by the link 29a, as shown in Figure 1.

It is of course desirable that the aforescribed liquid diverting apparatus be free from leakage. Hence, the first elbow 24 and the bottom end of the sleeve may mount sealing rings 52 between the coupling rings 54 utilized to connect the sleeve to pipe 18 and the J-shaped portion 30. Furthermore, it is desirable that the upper end of the rubber cylinder 32 act as a sealing means between the sleeve 22 and the depending pipe 18. To this end, the inner periphery of the upper end of the sleeve may be flared outwardly, as indicated at 56. Additionally, the upper end of the cylinder 32 may also flare outwardly at this point, as indicated at 58, to conform to the inner periphery of the sleeve at this point. With regard to the top coupling ring 60, its radially inturned flange 62 overlaps an outwardly extending radial lip 64 formed at the lower end of the pipe 18. By this arrangement, tightening the top coupling ring 60 upon the upper end of the sleeve 22 will urge the lip 64 downwardly against the top of the cylinder 32 forcing it against the outwardly flared inner periphery of the sleeve so as to thereby effect a seal between the pipe 18 and the sleeve. This arrangement also makes it possible to support the cylinder 32 within the sleeve solely by means of the top coupling ring 60. Hence, at such time as it becomes necessary to replace this cylinder, it is necessary only to unscrew the top coupling ring and lift out the old cylinder and insert a new cylinder.

It should be noted that it is not essential that the diverted water flow into a storage container, such as 16. But, instead, this water may be directly carried by a suitable piping system to such place as it is to be used. It should also be noted that the exact shape of the valve 40 is not critical, nor is the manner whereby it is caused to be moved into contact with the bottom end of the cylinder 32.

It will be apparent to those skilled in the art that various other modifications and changes may be made without departing from the spirit of the invention or the scope of the appended claim.

We claim:

Liquid diverting apparatus for use in a piping system which includes a depending pipe formed with an outwardly extending radial lip at its lower end, comprising: a sleeve adapted to be mounted vertically in said piping system with its upper end secured to the lower end of said depending pipe, the inner periphery of the upper end of said sleeve flaring outwardly, said sleeve being formed with a first elbow in its upper portion and a second elbow in its lower portion, both elbows and the upper and lower ends of said sleeve being externally threaded; top and bottom coupling rings threaded upon the upper and lower ends of said sleeve; said top coupling ring having a radially inturned flange which overlaps the lip of said depending pipe; a side coupling ring threaded upon said first elbow; an axially bored rubber cylinder concentrically mounted within said sleeve with its bottom end located below said first elbow and above said second elbow, the upper end of said cylinder being flared outwardly to conform to the inner periphery of said sleeve at this point whereby tightening of said top coupling ring will urge said lip downwardly against the top of said cylinder forcing it against the inner periphery of said sleeve so as to thereby effect a seal between said depending pipe and said sleeve, said cylinder also being formed with a radial bore aligned with said first elbow; a mounting element threaded upon said second elbow; a ball rockably retained between said mounting element and said second elbow; a rod extending into said sleeve from said ball; a cone-shaped valve pivotally secured to the distal end of said rod; and a lever affixed to the side of said ball remote from said sleeve, said lever being movable so as to urge said valve upwardly whereby it will seat against the bottom of said cylinder thereby sealing off said bore.

55.

WINIFRED E. PARKS.
HAROLD W. WEST.
